UNITED STATES PATENT OFFICE.

WILLIAM T. LINTNER AND JAMES T. DOWDALL, OF GLOVERSVILLE, NEW YORK.

DESIGN FOR A GLOVE

SPECIFICATION forming part of Design No. 29,086, dated July 19, 1898.

Application filed June 8, 1898. Serial No. 682,951. Term of patent 14 years.

To all whom it may concern:

Be it known that we, WILLIAM T. LINTNER and JAMES T. DOWDALL, citizens of the United States, residing at Gloversville, in the county of Fulton and State of New York, have invented and produced a new and original Design for Gloves, of which the following is a specification, reference being had to the accompanying drawings, forming part thereof.

- o Figure 1 shows a glove embodying our design, and Fig. 2 is an enlarged view of the embroidery thereon.

As shown in the accompanying drawings, the leading or material feature of our design consists of bands of embroidery on the backs of gloves, each band being composed of a rib

or draw, having a zigzag thread crossing it and zigzag stitches at the sides of said draw. The stitches at the sides of the draw are substantially parallel to those crossing the draw, as shown in the drawings.

Having described our invention, what we claim as new and desire to secure by Letters Patent, is—

The design for a glove substantially as herein shown and described.

WILLIAM T. LINTNER.
JAMES T. DOWDALL.
